UNITED STATES PATENT OFFICE.

CHRISTOPHER HAPPE, OF WHITTIER, CALIFORNIA.

TELEGRAPH MACHINE.

Application filed May 10, 1926. Serial No. 108,017.

My invention relates to improvements in telegraphing machines and more particularly to machines for sending code messages.

An object of my invention is to provide a machine in which relatively movable code signal contacts in an electrical circuit are arranged for actuation by letter designated key levers.

A further object is to provide a machine comprising a typewriting machine having a lettered keyboard and a code sending machine coupled for operation with the writing machine whereby as a typewritten copy is made a code message is sent as an exact duplicate of the written copy.

My improvements consist in the novel construction, arrangement and combination of parts as hereinafter fully, clearly and concisely described, definitely pointed out in my claims and illustrated by the accompanying drawings, (3 sheets) in which:

Fig. 1 is a front elevation of the telegraphing machine of my invention;

Fig. 2 is an end elevation of the machine shown in Fig. 1, showing its relation to a typewriting machine, which latter is shown only fragmentarily;

Fig. 3 is a detail perspective of one of the code wheels;

Fig. 4 is a detail sectional elevation, taken on the line 4—4 of Fig. 2 showing the relation of the actuating levers of the telegraphing machine with the key levers of a typewriting machine;

Fig. 5 is an enlarged elevation showing several of the code elements, one of which is shown in vertical section, and another of which shows a key actuating member;

Fig. 6 is a transverse section taken on the line 6—6 of Fig. 5;

Fig. 7 is a section taken on the line 7—7 of Fig. 5 showing a relating means for the relatively movable code contact elements.

Referring more specifically to the drawings, A designates a frame comprising a base 10, spaced standards or cheeks 11, a driven shaft 12, a shaft 13 for the support of the actuating levers and an insulating guide bar 14 for certain of the actuating mechanism.

The shaft 12 is arranged for constant rotation and the gear wheel 15 represents one of a train of reduction gear elements for connection with a motor not shown. Mounted on the shaft 12 is a plurality of code wheels

16, which as shown in Fig. 3, comprises a periphery composed of relatively insulated code contacts 17 and the wheel is fixed for rotation with the shaft as by a pin 18.

Embracing and surrounding each code wheel is a disc-shaped body 19 of insulating material, which is loosely rotatably carried on the shaft 12, in whose one lateral face is a depression 20 to receive the code wheel and through which from the periphery to the depression is formed a bore 21.

In the end of the bore next the periphery is fitted a metallic seat 22.

A brush 23 is placed in the bore for engagement with the code wheel, a coil spring 24 placed next the brush and an adjustable spring abutment 25, formed as a screw plug, is fixed in the seat 22.

A band 26 of metal is placed around each of the disks 19 with its free ends extended therebeneath and between which is detachably secured as by a bolt 27, a tubular fitting 28. Into this fitting a headed bolt 29 is slipped and extended through the guide bar 14.

Mounted on the shaft 13, carried in bearings 30, which are insulated from the frame, as by the blocks 31, is a lever 32, for each band 26, which lever straddles the bolt 29, as best shown in Fig. 5 and which bolt carries an adjustable nut 33 which serves to pull the band upon a depression of the lever.

A restoring spring 34 impinging between the guide bar 14 and a nut 36 carried on the bolt is provided for each lever 32.

Flanges 37, preferably formed as metallic rings, are carried by each disc-body 19 for holding of the bands properly related.

In Fig. 2 the fragmentary bar-shaped element B represents a typewriting machine of any standard design and such fragment is the showing of one of the key levers, which connects with an actuating lever 32 of the telegraphing machine, such as in Fig. 4, in a manner to depress the lever 32 upon a printing movement of the key lever of the typewriter.

In order that the brush 23 be held in proximal relation to the code contacts 17, I provide a locator which comprises a tripper arm 38 rotatable with the code wheel and a spring held detent 39 carried by the disc-body 19, which operates to normally position the brush away from the contacts 17, as shown in Fig. 6, but which upon a stop-

ping of the disk body, as by an action of a band, as a brake, releases the code wheel from the brush carrying body 19 so that in the continued movement of the code wheel 5 code-contacts will be delivered from the points 17 to the brush.

In operation, upon the depression of a lever 32, the band is tightened about a disc 19 and the brush stopped, so that the rotating 10 code wheel will deliver an interrupted current to the brush and over a line to a standard telegraph receiving set.

By tightening the band 26 about the rotating brush-carrying disc 19 relative motion is 15 produced between the selective code wheel and contact in such a small fraction of a second as to secure accurate transmission of signals, and yet no objectionable impact occurs between the continuously rotating element 20 and the operatively stationary element. In devices of this class wherein pawls and ratchets are employed, accuracy of transmission under high speed is interfered with. If an unyielding stop is suddenly thrown 25 into the path of a rapidly rotating element, severe jar and wear producing friction is imposed upon the machine. So far as I am aware, it is now in the art to which this invention pertains to apply to one of two rotating parts a key-operable brake of any kind, in this relation, in order to produce 30 relative motion between a code wheel and its contact.

In order to meet the ordinary speed of a typist the code wheels must rotate approximately at a speed of three hundred revolutions per minute. This machine will so operate without any damaging friction even when no lubricant is applied to parts adjacent to the code wheels.

The circuit as shown is, from the binding post 40, through the frame 11, to shaft 12 to code wheel 16, brush 23, band 26, bolt 29, lever 32, shaft 13, bearing 30 to binding 45 post 41.

I claim:—

1. A telegraphing machine comprising a frame, a shaft rotatably supported in the frame, a gear rotatably connected with the shaft to provide a continuous drive therefor, in operation, a code wheel fixed to rotate with the recited driven shaft, a disc-shaped brush holder embracing and surrounding the code wheel and loosely rotatably carried by the shaft, a brush carried by the brush holder for contact with the code wheel, a locator, 50 between said brush holder, and code wheel, comprising relatively releasable elements, a friction brake device for the brush holder, 55 means for connecting the brake device with an actuating lever, and means for connect-

ing the code wheel and the brake device in an electrical circuit.

2. In combination with a type bar actuating lever of a typewriting machine, a telegraph sending mechanism comprising a rotatable and continuously driven code wheel, a brush and a holder therefor, revoluble about the code wheel, releasable means for causing the brush holder normally to rotate 65 with the code wheel, a friction brake device for the brush holder, means for connecting the brake device with the recited actuating lever and means for connecting the code wheel and brake device in an electric circuit. 75

3. A telegraphing machine comprising normally rotating code wheels and contacts, a friction brake to arrest the selected contact to produce relative rotation between 80 said wheels and contacts, and key-operable means to apply said brake.

4. A telegraphing machine comprising code wheels and contacts normally rotating in unison about a common axis, a friction 85 brake to arrest rotation of the selected contact to produce relative rotation between said wheels and contacts, key-operable means to apply said brake, and a yielding locator to releasably couple together each code wheel 90 and its contact after operation thereof.

5. A telegraphing machine comprising a continuously rotating shaft, a code wheel fixed thereto, a disc loosely carried by said shaft, said disc having a peripheral portion 95 extending around said code wheel, a brake band extending around said disc, key-operable means to apply said brake band to said disc, means carried by said peripheral portion of the code wheel to make and break 100 an electric current to produce signals, and an electric circuit adapted to be completed and broken by the application of said brake band to said disc.

6. A telegraphing machine comprising a 105 continuously rotating shaft, a code wheel fixed thereto, a disc loosely carried by said shaft, said disc having a peripheral portion extending around said code wheel, a brake band extending around said disc, key-operable 110 means to apply said brake band to said disc, means carried by said peripheral portion of the code wheel to make and break an electric current between said code wheel and brake band to transmit signals, and 115 means for completing an electric circuit of which said brake band and code disc form a part.

In testimony whereof, I have affixed my signature.

CHRISTOPHER HAPPE.
